PNEUMATIC TENSIONING AND EVERTING ARRANGEMENTS FOR CYLINDRICAL STOCKING KNITTING MACHINES

Riccardo Tenconi, Varese, Italy, assignor to Marcella Sessa Moretta, Varese, Italy, a citizen of Italy

Filed July 5, 1960, Ser. No. 40,972

Claims priority, application Italy July 4, 1959

6 Claims. (Cl. 66—149)

This invention relates to improvements in pneumatic hose tensioning and evertng means for cylindrical knitting machines, intended chiefly for the production of stockings, of the type described in the prior Italian Patent No. 556,014.

The above mentioned patent discloses a pneumatic tensioning device constituted substantially by a tube arranged coaxially inside the needle cylinder of the knitting machine and provided with means whereby said tube inside which the hose travels downwardly during its formation, is rotated in synchronism with the needle cylinder.

Thus, there is no relative angular movement between the hose or stocking being produced and the tube so that uniform downward movement of the hose is achieved.

With the tensioning means described above, the hose is tensioned as it is being formed throughout its length, and therefore the tube inside which the hose moves downwardly should have a corresponding length which requires a certain minimum height for the frame or knitting machine. Furthermore, the removal of the finished hose, everted or otherwise, cannot be effected directly underneath the needle cylinder without further increasing the height of the machine.

This leads to the necessity of providing complex connections between the tube arranged coaxially inside the needle cylinder and a lateral tube leading either to the air suction means or to the means provided for removing the finished hose.

Accordingly, it is an object of this invention to provide a relatively simple hose tensioning and evertng arrangement for circular knitting machines, which arrangement leads to a substantial reduction of the height of the frame and also provides for a delivery of the hose directly to a point underneath the needle cylinder.

The above results are achieved, according to my invention, by means of an arrangement including a tube disposed rotatably and coaxially inside the needle cylinder and connected with the latter, so as to synchronously follow its continuous rotary and reciprocatory movements, a perforated carrier element mounted on the inner tube adjacent the lower end of the latter, the annular gap between the cylinder and the inner tube being open at its upper end and communicating at its lower end with a closed casing, said inner tube opening at its lower end into a chamber lying underneath the casing; and a valve system operative to alternately connect the casing and chamber with suction means, so that, during the formation of the hose, the latter is subjected to suction and is tensioned by a stream of air directed downwardly through said gap and collects on the rotary carrier at the lower end of the inner tube, while, upon completion of the stocking or hose, air is sucked downwardly in the inner tube and urges the finished stocking out of the gap into the inside of the tube, whereby the stocking is automatically turned inside out or everted and is delivered into the chamber communicating with the lower end of the tube.

Inside the needle cylinder and practically in contact with the hose may be arranged a stationary tube having its upper end flared outwardly almost into contact with the upper end of the needle cylinder, so as to form a passage or annular gap for the stocking between said

2

stationary tube and the central or inner rotary tube, while the lower end of the stationary tube is connected with the casing into which said gap opens.

During the evertng of the stockings, the space enclosed by the casing and, thus also said gap may be connected with the delivery end or pressure outlet of the fan or blower having its inlet constituting the suction means, while, at the same time, the inside of the rotary inner tube is connected with the suction end or inlet of the fan. Thus, a reinforcing effect is obtained, so that the evertng of the stocking is obtained more reliably and more speedily.

The chamber into which the rotary inner tube opens and which lies coaxially underneath the needle cylinder may be provided with a gate which opens during the formation of the stocking and closes during the evertng of the latter. The above novel features of the hose-tensioning and evertng means lead to substantial advantages over the known arrangements. The downward movement of the hose is obtained in an unhindered manner by reason of the provision of the inner tube with the rotary carrier for the hose during its formation, which carrier constrains said hose to follow synchronously the movements of the needle cylinder. Since the hose is no longer tensioned throughout its length, it is obvious that the height of the tube is substantially reduced; thus, it is possible, without increasing the height of the knitting machine, to obtain underneath the needle cylinder the space required for removing the finished and automatically everted hose and for accommodating a suitable container into which each hose is dropped after its formation.

The above, and other objects, features and advantages of the invention, will be apparent in the following detailed description of a preferred embodiment thereof which is to be read in connection with the accompanying drawings, wherein: FIG. 1 shows the needle cylinder in vertical cross-section with the tensioning and evertng means shown in the condition thereof during the formation of a stocking, FIG. 2 is a view similar to FIG. 1, but with the tensioning and evertng means being shown conditioned for evertng the finished stocking, and FIG. 3 illustrates diagrammatically the operation of the arrangement according to my invention.

The drawings illustrate diagrammatically only those parts of a cylindrical knitting machine, of a type known per se, intended for the production of stockings, which parts are necessary to the understanding of the invention. Obviously, all the other parts of the knitting machine may be constructed and made to operate in a conventional manner.

The following description is limited to the detailed disclosure of my improved arrangement with only casual reference being made to certain parts of the needle cylinder with which said arrangement is associated.

55 In FIGS. 1 and 2, the reference numeral 1 generally identifies the frame of the knitting machine in which the cylinder 2 carrying the needles 3 is rotatably mounted. Inside the cylinder 2 is arranged a stationary tube 30 lying practically in contact with the inner wall of the needle cylinder. The upper end of tube 30 is in the shape of a funnel 5 which extends closely adjacent to the upper end of the cylinder 2. At its lower end projecting beyond the cylinder 2, the tube 30 is connected with a stationary casing 50 secured to the frame 1 of the machine. A second tube 31 is arranged coaxially inside the tube 30 and has a smaller diameter than the latter. The upper end of tube 31 ends in a plane slightly lower than the upper end of the tube 30. Said inner tube 31 is carried rotatably at its lower end by the casing 50. 60 Further, the tube 31 is connected mechanically with the cylinder 2 so as to be rotated with the latter, for example, through the gear wheels 19 and 20 keyed to a common ver-

tical shaft 21 and respectively meshing with a toothed ring 19' secured to the cylinder 2, and with the toothed ring 20' secured to the inner tube 31. The gears 19', 19, 20 and 20' provide a 1:1 transmission ratio so that the tube 31 revolves in perfect synchronism with and at the same speed as the cylinder 2. Near the lower end of the rotary tube 31 there is secured a carrier 51, the bottom of which is perforated and extends upwardly and outwardly to an outer periphery surrounded with a slight clearance by the casing 50. The carrier 51 rotates with the tube 31.

The ends of the tube 31 are both open and its lower end opens into a stationary chamber 15 arranged coaxially underneath the cylinder 2. A gate 22, controlled through levers 23 and 24 by a suitable cam 27 on the control drum 26 of the knitting machine is adapted to close the lower end of the chamber 15. The lever 24 is subjected to the action of a spring 52 which urges the gate into its open position, as shown in full lines on FIG. 1. It is only when the end of the lever 24 meets a projection on the annular cam 27 that the gate 22 is closed (see FIG. 2). The casing 50 further carries two pipes 53 and 54 connected respectively with the suction and delivery ends of a suction fan 17 of a known type (see diagrammatic FIG. 3) driven by a motor 18. The pipe 54 is selectively connected through a valve 28a with the inside of the casing 50 (FIG. 2) or with the atmosphere (FIG. 1).

In a similar manner, the tube 53 may be connected selectively with a connection 55 opening into the chamber 15 through a perforated wall 56 of the latter (FIG. 2), or with the inside of the casing 50. To this end, there is provided a valve 28 which is controlled together with the valve 28a by the same lever 24 which controls the gate 22 of the casing 15 (FIG. 1).

The operation of the hose-tensioning and evertng means described above is as follows:

During the operation of the knitting machines for the formation of a stocking, the control lever 24 is moved by the spring 52 to open the gate 22 and to hold the valves 28 and 28a in the positions shown in full lines on FIG. 1 so that the suction pipe 53 is connected with the inside of the casing 50 and the delivery pipe 54 is connected with the atmosphere. This produces a suction or downward flow of the air in the gap separating the tubes 30 and 31, as shown by the arrows on FIG. 1, and, similarly, by the arrows drawn in solid lines on FIG. 3. Air is also sucked upwardly in the inner tube 31, so as to pass out of the latter into the gap between the tubes 30 and 31 and over the upper edge of the inner tube, as shown by the same arrows.

An energetic downwardly directed stream of air passes therefore through the hose that is being formed in the gap between said tubes 30 and 31. At the same time, the inner tube 31 and the perforated carrier 51 rotate synchronously with the needle cylinder 2, and the stream of air passes through the perforated carrier 51 since the latter rotates with its peripheral edge in the immediate proximity of the wall of the casing 50 surrounding it. When the hose has attained a sufficient length to cause its free end to engage the carrier, it lies during the remainder of its formation on said carrier, so that it is constrained by the latter to follow the rotary movement of the cylinder 2.

It should be noted that by reason of the upward flow of air through the inside of the tube 31, the air producing the tensioning of the hose does not entirely pass through the gap between the cylinder and the dial so that the needles are stressed to a much lesser amount.

When the stocking is completed, the cam 27 on the control drum 26 causes, through the levers 24 and 23, the closing of the gate 22 and the change in position of the valves 28 and 28a (FIG. 2), so that the suction tube 53 now communicates through the connection 55, the perforated wall 56, the chamber 15 closed by the gate

22, with the inside of the rotary tube 31, while, on the other hand, the air delivery tube 54 is connected through the casing 50 with the gap between the tubes 31 and 30.

The directions of the air streams sucked out of the inside of the tube 31 and blown into the gap between the two tubes are reversed so that air flows upwardly in the gap between tubes 30 and 31 and downwardly in the tube 31, as represented by the arrows on FIG. 2 and the arrows in broken lines on FIG. 3. This leads automatically to the evertng or turning inside out of the finished hose which passes through the tube 31, so as to drop into the chamber 15 and onto the closed gate 22. The operating cycle is repeated with the different parts being returned to the positions illustrated in FIG. 1. The previously formed stocking passes through the open gate 22 and drops into a container (not shown) lying underneath the latter.

The advantages and the simple structure and operation of the arrangement embodying the invention for tensioning and evertng the hose are apparent in the above detailed description thereof.

Although a particular embodiment of the invention has been described in detail herein, it is to be understood that the invention is not limited to that precise embodiment, and that various changes and modifications may be effected therein without departing from the scope or spirit of the invention, except as defined in the appended claims.

What I claim is:

1. A fabric-tensioning and evertng arrangement for a cylindrical hose-producing knitting machine, comprising a needle cylinder, an inner tube extending coaxially within said needle cylinder and rotating in synchronism with the latter, said inner tube being spaced radially from said needle cylinder to define an annular gap therebetween opening freely at its upper end, a perforated carrier fixed to the lower end of said inner tube and directed outwardly and upwardly with reference thereto, a stationary closed casing around said carrier and into which said gap opens at its lower end, means defining a stationary chamber lying underneath said casing and having the lower end of said inner tube opening therein, air suction means, and a valve system operative to alternatively connect said casing and said chamber with said suction means to produce, during the formation of the hose, a stream of air directed downwardly through the gap to suck the hose towards the lower end of the gap and onto said carrier in said casing and, upon completion of the hose, to direct the stream of air upwardly in said gap over the upper end of the inner tube and then downwardly in the latter so as to evert the hose and allow it to drop through the inner tube into said chamber at the lower end of the latter.

2. A fabric-tensioning and evertng arrangement for a cylindrical hose-producing knitting machine as in claim 1; wherein said means defining a stationary chamber has a normally closed gate at the bottom of said chamber, said gate being adapted to open for permitting removal of the completed hose from said chamber.

3. A fabric-tensioning and evertng arrangement for a cylindrical hose-producing knitting machine comprising a needle cylinder, an inner tube extending coaxially within said needle cylinder and rotating in synchronism with the latter, a perforated carrier fixed to the lower end of said inner tube and directed outwardly and upwardly with reference thereto, a stationary tube disposed coaxially within said needle cylinder and spaced radially outward from said inner tube to define an annular gap therebetween opening freely at its upper end, a stationary closed casing extending from said stationary tube and into which said gap opens at its lower end with said carrier being located in said casing, means defining a stationary chamber lying underneath said casing and having the lower end of said inner tube opening therein, air suction means, and a valve system operative to alternatively connect said casing and said chamber with the suction means to produce, during

the formation of the hose, a stream of air directed downwardly through the gap to suck the hose toward the lower end of the gap onto said carrier in said casing and, upon completion of the hose, to direct the stream of air upwardly in said gap over the upper edge of said inner tube and then downwardly in the latter so as to evert the hose and allow it to drop through the inner tube into said chamber at the lower end of the latter.

4. A fabric-tensioning and evertng arrangement for a cylindrical hose-producing knitting machine, comprising a needle cylinder, an inner tube extending coaxially within said needle cylinder and rotating in synchronism with the latter, a perforated carrier fixed on the lower end of the inner tube and directed outwardly with reference thereto, said inner tube being spaced radially from the needle cylinder to define a cylindrical gap therebetween opening freely at its upper end, a closed casing containing said carrier and into which said gap opens at its lower end, means defining a chamber lying underneath said casing and having the lower end of the inner tube opening therein, air suction means having an air inlet and an air exhaust, a first pipe including a deflecting valve adapted to occupy first and second positions to alternatively connect said air inlet of the suction means with said casing and said chamber, respectively, a second pipe including a deflecting valve adapted to occupy first and second positions to alternatively connect said air exhaust of the suc-

tion means with the atmosphere and with said casing, respectively, and means controlling the deflecting valves to alternatively produce, during the formation of the hose, a stream of air directed downwardly through the gap to suck the hose towards the lower end of the gap and onto said carrier and, upon completion of the hose, to direct the stream of air upwardly in said gap over the upper edge of said inner tube and then downwardly through the latter to evert the hose and allow it to drop through the inner tube into said chamber at the lower end of the latter.

5. A fabric-tensioning and evertng arrangement for a cylindrical hose-producing knitting machine as in claim 4; wherein said means controlling the deflecting valves includes a common control member for both deflecting valves included in said first and second pipes and operative to simultaneously shift said valves between said first and second positions thereof.

6. A fabric-tensioning and evertng arrangement for a cylindrical hose-producing knitting machine as in claim 5; wherein said means defining the chamber has a normally closed gate at the bottom of said chamber, said gate being adapted to be opened so as to permit removal of the completed hose from said chamber.
